Fig. 1.

Fig. 3.

Fig. 2.

Fig. 4.

Fig. 5.

Fig. 1 is a front elevational view of a door knob showing my new design.

Fig. 2 is a side elevation of Fig. 1;

Fig. 3 is a view similar to Fig. 2 but with the knob turned to further illustrate its configuration at one of the corners;

Fig. 4 is a cross-section taken on line 4—4 of Fig. 1; and

Fig. 5 is a reduced scale cross-section taken on line 5—5 of Fig. 1.

The essential features of my design reside in the portions shown in full lines.

I claim:

The ornamental design for a door knob, substantially as shown and described.
